UNITED STATES PATENT OFFICE.

JOHN C. POLAND, OF BOSTON, MASSACHUSETTS.

STARCHING-MACHINE.

SPECIFICATION forming part of Letters Patent No. 485,980, dated November 8, 1892.

Application filed March 26, 1890. Serial No. 345,358. (No model.)

To all whom it may concern:

Be it known that I, JOHN C. POLAND, of Boston, in the county of Suffolk and State of Massachusetts, have invented certain new and 5 useful Improvements in Starching-Machines, of which the following is a specification.

This invention has for its object to provide means for rapidly and thoroughly forcing starch into the fibers and meshes of shirt-bosoms and other articles to be starched, and, further, to provide a simple and effective machine for starching shirt-bosoms, adapted to be set in operation by an attendant and thereafter to continue in operation without attention until the operator desires to stop the operation, so that the operator, after placing a shirt-bosom in position in the machine and adjusting the same, can, while the bosom is being starched, attend to other matters, such 20 as the preparation of another shirt-bosom for the machine.

To these ends the invention consists in the improvements which I will now proceed to describe and claim.

25 Of the accompanying drawings, forming a part of this specification, Figure 1 represents a front elevation of a starching-machine embodying my invention. Fig. 2 represents an end elevation of the same. Fig. 3 represents 30 a similar elevation showing the machine stopped. Fig. 3^a represents a perspective view of portions of the machine. Fig. 4 represents an enlarged section on line 4-4 of Fig. 2. Fig. 5 represents a similar section of a 35 modification showing the starch-box as having a ribbed bottom. Fig. 6 represents a sectional view showing another modification.

The same letters and figures of reference indicate the same parts in all the figures.

40 In the drawings, *a* represents the supporting-frame, on which is mounted a box or casing *b*, which is open at its top and is provided with a vertically-movable side piece 2, which slides in vertical guides in the end pieces of 45 the casing, said side piece being adapted to be raised, as hereinafter described, to permit the insertion of a shirt-bosom into the casing under said side piece, the latter acting to hold the shirt-bosom in place in the casing and to 50 prevent the starch from coming in contact with the other parts of the shirt, as presently described.

c, Figs. 1 and 4, represents a rocking starch-box adapted to be placed in the casing *b*, so that its bottom, which is preferably curved, 55 may rest upon the shirt-bosom placed in said casing. The bottom of the starch-box is provided with numerous perforations *d* for the passage of the starch from the interior of the box to the fabric on which it rests. 60

To the starch-box *c* is attached a yoke *e*, the upper portion of which is pivotally connected with one end of a connecting-rod *f*, the other end of which is pivoted to one arm of a bell-crank lever *g*. Said lever *g* is pivoted at *h* 65 to a bracket *i* on the frame *a*, and its other arm extends inwardly under the casing *b* and is there connected by a rod or pitman *j* with a wrist-pin *k*, eccentrically affixed to a disk *m* on the driving-shaft *n*, the latter being 70 journaled in bearings at the lower portion of the frame *a*. The shaft *n* is provided with a fast-pulley *o*, on which runs the driving-belt *p*, which imparts motion to the shaft and causes it, through the disk *m*, wrist-pin *k*, 75 connecting-rod *j*, bell-crank lever *g*, and connecting-rod *f*, to rock the starch-box in the casing *b*, and thus cause the curved bottom of said starch-box to act with a rolling pressure upon the shirt placed between it and the bottom of the casing. 80

The starch in the box *c* oozes through the holes *d* and is spread upon the shirt-bosom by the rocking-motion action of the box-bottom, the starch being at the same time forced into 85 the meshes of the fabric and thoroughly incorporated therein by a sufficient continuance of said rocking motion, the bottom of the box being rigid and acting percussively on the goods when the box is rocked. 90

q represents a lever, which is pivoted at *r* to a standard *s*, affixed to the frame *a* and projecting above the casing *b*. One end of said lever is connected by a chain *a'* or other suitable connecting means with the yoke *e* on the 95 starch-box, so that by a movement of said lever, which will raise the said end, the starch-box will be raised from the fabric on which it bears in the casing *b*, thus permitting the removal of said fabric. The lever *q* is connected by a rod *t* with a foot-lever or treadle *u*, which is pivoted at *w* to an arm or bracket *x* on the frame *a*. The forward end of the treadle *u* is provided with a foot-piece *u'*, 100

which is formed to be engaged and held in a depressed position by a latch v , said latch being pivoted to a cross-bar y , attached to the frame a . When the latch v is engaged with the foot-piece u' , as shown in Figs. 1 and 2, the treadle is held thereby against the stress of a spring z , which is arranged to normally pull down the rear end of the lever q , and thus raise the forward end of said lever with the starch-box c . The latch v therefore prevents the action of said spring and holds the lever q in position to permit the starch-box to rest upon the shirt-bosom or other article inserted in the casing b .

15 c' represents a belt-shipper, which is fitted to slide in guides on a bracket b' , attached to the frame a , said shipper being provided with pins $d' d'$ or other suitable devices, whereby it is enabled to engage the belt p and move 20 the same from the fast pulley o onto a loose pulley o' , or reverse this operation.

25 e' represents a lever pivoted at f' to the frame a and connected at its lower end by a rod g' with the pivoted latch v . The lever e' is provided with a slot h' , which receives a pin i' on the belt-shipper c' , said shipper being thus engaged with the lever e' , so that the oscillating movements of said lever, caused by the movements of the latch v , as presently described, 30 will move the shipper horizontally. The lever e' is arranged so that when the treadle u is in the position shown in Figs. 1 and 2 the shipper will be held in position to engage the belt p with the fast pulley o ; but when the 35 treadle is released by disconnecting the latch v from it the shipper will be moved to position to engage the belt with the loose pulley o' .

40 A spring v^2 , connected at one end with the rod g' and at the other end with the supporting-frame, normally holds the belt-shipper and the latch in the positions shown in Fig. 2, the belt-shipper being thus yieldingly held 45 in position to keep the belt on the fast pulley, while the latch v is yieldingly held in position to engage the treadle u , as described hereinafter.

45 The treadle u is provided with arms $u'' u''$, to which are pivotally connected rods $j' j'$, which extend upwardly and pass through 50 ears or lugs k' on the sliding front piece 2 of the casing b . The rods j' are provided below said lugs with collars or enlargements m' , which are arranged to strike the lugs k' when the rods j' are moved upwardly by the treadle 55 when the latter is moving from the position shown in Fig. 2 to that shown in Fig. 3. The front piece 2 is therefore raised when the treadle u is released, so that the shirt within the casing b may be readily removed. When 60 the treadle u is again depressed and held by the latch v , springs p' , interposed between the upper sides of said lugs and nuts or collars q' on the rods j' , force the sliding side piece 2 downwardly with a yielding pressure 65 upon the portions of the shirt or other garment that projects from the interior of the casing, so that the garment is clamped be-

tween the lower edge of the side piece 2 and the surface of a table r' , which is attached to the frame a and is flush with the bottom of the casing b , the portions of the garment that project from the casing being protected by the sliding side piece, so that starch cannot reach them from within the casing.

70 The operation of the machine above described is as follows: The treadle u being released and held by the spring z in the position shown in Fig. 3 and the belt-shipper being held in its inoperative position by the engagement of the latch v^3 with the rod g' , so that the belt is on the loose pulley and the starch-box at rest, the operator inserts the bosom portion of a shirt under the raised side piece 2 of the casing, leaving the portion to be starched upon the bottom of the casing. 80 He then depresses the treadle u , and thus permits the starch-box to bear on the bosom on the bottom of the casing and also depresses the sliding side piece 2, causing it to bear on the projecting portion of the shirt. The depressed end of the treadle is locked in the position shown in Fig. 2 by means of the latch v , the latter being forced forward by the spring v^2 , which at the same time moves the belt-shipper to position to engage the belt with 85 the fast pulley, and thus impart the rocking motion to the starch-box. It should be here stated that when the latch v is pressed back by the operator to release the treadle and shift the belt to the loose pulley, as shown in Fig. 3, said latch is prevented from returning to the position shown in Fig. 2 by means of a second latch v^3 , which is pivoted to a fixed ear or bracket v^7 , and engages a shoulder v^4 on the rod g' when the latter is pressed back 90 to the position shown in Fig. 3. The latch v^3 has a projecting arm v^5 , which is located under the treadle u , as shown in Fig. 1, and is arranged to be depressed by the treadle u when the latter is being depressed, the latch v^3 being thereby raised and disengaged from the rod g' , so that the spring v^2 is permitted 95 to move the belt-shipper into position to engage the belt with the fast pulley and to engage the latch v with the depressed treadle. 100 The machine is therefore set in operation, the starch-box being rocked by the described connections between it and the shaft n . The operator may now leave the machine until the starch has been sufficiently worked into the 105 shirt-bosom. Hence he is enabled to attend to other duties during the said operation, such as the preparation of another shirt for insertion in the casing. After the shirt has been sufficiently starched the operator by pushing 110 back the latch v moves the belt-shipper into position to stop the rocking motion of the starch-box and at the same time releases the treadle, whereupon the spring z acts to shift the lever q and treadle u to the position 115 shown in Fig. 3, and thereby raises the sliding side piece 2 of the casing, so that the entire shirt is released. It will be seen, therefore, that the depression of the treadle u per-

forms all the operation required to set the machine in operation and secure the shirt in place, while the movement of the latch *v* from the position shown in Fig. 2 to that shown in Fig. 3 performs all the operations required to release the shirt, permit its free removal, and also to stop the operation of the machine. The machine is therefore adapted to be very easily and quickly controlled without the employment of skilled labor, the operator having only to depress the treadle and engage the latch *v* with it to perform one set of operations and push back the latch *v* to perform the other set of operations.

15 *a''* represents a starch-reservoir, which is supported by a bracket *b''*, attached to the frame *a* or to the casing *b*, said reservoir having a faucet *c''*, which is arranged to deliver starch into the starch-box *c*.

20 I do not limit myself to the precise details of construction of many of the parts here shown, and may vary the same without departing from the spirit of my invention.

A weight may be substituted for the spring 25 *z* as the means for raising the starch-box, and a hand-lever may be substituted for the treadle *u* as the means for depressing the starch-box.

It will be seen that when the starch-box is 30 depressed its flexible connection with the lever *q* is such that the entire weight of the box bears on the shirt-bosom and acts to press the starch into the meshes of the bosom.

I may use the starch-box *c'*, the bottom of 35 which is flat, as shown in Fig. 6, instead of being curved; but I prefer the curved form, because it enables the line of pressure to progress along the shirt-bosom and operates without noise.

40 The starch-box shown in Fig. 6 may be rocked by the same means that are represented in Figs. 1, 2, and 3 to rock the starch-box shown in these figures.

Fig. 5 shows the bottom of the starch-box 45 and the bottom of the casing ribbed or fluted, the casing being lettered *b'* instead of *b*, as in the other figures, because its bottom is ribbed.

I claim—

1. In a starching-machine, the combination 50 of a bed or support for the article to be starched, a starch-box adapted to rock on said bed, means, as a spring and connections between the same and the starch-box, whereby the latter is normally raised above the bed, a lever connected with the starch-box by suitable intermediate devices and adapted to be moved into position to prevent the action of the box-raising spring, and thereby permit the starch-box to rest on the bed, and a latch 55 or detent whereby the lever may be held in said position, as set forth.

2. In a starching-machine, the combination 60 of a bed or support for the article to be starched, a starch-box adapted to rock on said bed, means, as a spring and connections between the same and the starch-box, whereby the latter is normally raised above the bed, a

lever connected with the starch-box by suitable intermediate devices and adapted to be moved into position to prevent the action of the box-raising spring, and thereby permit the starch-box to rest on the bed, a latch or detent whereby the lever may be held in said position, a driving-shaft journaled in bearings on the frame of the machine and provided 70 with a fast pulley and with a loose pulley, connections between said shaft and the starch-box, whereby the latter is rocked by the rotation of the shaft, a belt-shipper engaged with the driving-belt, and connections between said 75 shipper and the treadle-engaging latch, whereby the displacement of said latch is caused to shift the belt and stop the rocking motion of the starch-box, as set forth.

3. In a starching-machine, the combination 80 of a support for the article to be starched, a starch-box over said support, having a perforated bottom, means for rocking said starch-box, a pivoted lever connected with the starch-box, a spring *z*, arranged to move said lever 90 to raise the starch-box from the support, a treadle connected with said lever and adapted to move the latter in the direction required to depress the starch-box, and a detent whereby the treadle may be held against the force of 95 the box-raising spring, as set forth.

4. In a starching-machine, the combination 100 of a casing *b*, a rocking starch-box therein having a perforated bottom, a sliding side piece forming a part of said casing, a pivoted lever connected with the starch-box, a spring adapted to raise the starch-box through said 105 lever, a treadle pivoted to the frame of the machine, a lock or detent for the treadle, and connections between the starch-box lever and the treadle and between the treadle and the sliding front piece, whereby the front piece is raised simultaneously with the starch-box by the action of the spring when the treadle is released, as set forth.

5. In a starching-machine, the combination 110 of a support for the article to be starched, a starch-box having a perforated bottom adapted to rock on said support, a bell-crank lever *g*, pivoted to a fixed support and having one 115 of its arms connected by rod *f* with the rocking starch-box, and a driving-shaft having an eccentric wrist-pin *k*, connected by rod or pitman *j* with the other arm of said lever, as set forth.

6. The combination of a support for the article to be starched, a rocking starch-box having a perforated bottom, a lever pivoted to a fixed support and connected by a flexible connection with said starch-box, a spring arranged to move said lever in the direction required to cause the latter to raise the starch-box, a treadle pivoted to the frame of the machine, a rod *t*, connecting said treadle with the starch-box-raising lever, a latch or detent 125 adapted to hold the treadle against the stress of the starch-box-raising spring, a driving-shaft journaled in bearings in the frame of the machine and provided with a fast pulley 130.

and a loose pulley, connections between said shaft and the starch-box, whereby the latter is oscillated by the rotation of the shaft, a belt-shipper engaged with the belt that transmits motion to the driving-shaft, and connections between said belt-shipper and the latch or detent, whereby the belt-shipper is held in position to engage the driving-belt with the fast pulley when the treadle is locked by its detent and is moved to engage the belt with the loose pulley by the displacement of said latch from its treadle-holding position, as set forth.

7. The combination of the casing *b*, having the sliding front piece 2, the table *r'*, extending outwardly from said casing, the starch-box, its raising-lever, and the lever-operating spring, the pivoted treadle connected with said lever, the rods *j' j'*, connected with said

treadle and passing through lugs *k'* on the front piece 2 of the casing, the shoulders or enlargements *m'* on the rods *j'* below the lugs *k'*, the shoulders or enlargements *q'* on said rods above said lugs, and springs interposed between the lugs and the shoulders *q'*, where-by a yielding downward pressure is imparted to the sliding piece 2 when the treadle is depressed, and a latch or detent to hold said lever in a depressed position, as set forth.

In testimony whereof I have signed my name to this specification, in the presence of two subscribing witnesses, this 20th day of March, A. D. 1890.

JOHN C. POLAND.
